COMBINED SLICING AND STORING DEVICE

Carl W. Paul, New York, N. Y.

Application May 25, 1950, Serial No. 10,150

Term of patent 7 years

(Cl. D44—29)

To all whom it may concern:

Be it known that I, Carl Wm. Paul, a citizen of the United States of America, residing at New York city, in the county of New York and State of New York, have invented a new, original, and ornamental Design for Combined Slicing and Storing Device, of which the following is a specification, reference being had to the accompanying drawing, forming part thereof.

In the drawing

Fig. 1 is a front perspective view of the combined slicing and storing device showing my new design, said device being shown in an extended position with the cover thereof raised;

Fig. 2 is a side elevational view thereof with the device in the same position as in Fig. 1;

Fig. 3 is a side elevation of the device in closed position;

Fig. 4 is a top plan view thereof;
Fig. 5 is a front elevational view thereof; and,
Fig. 6 is a rear elevational view thereof.

I claim:

The ornamental design for a combined slicing and storing device, substantially as shown.

CARL WM. PAUL.
